(57) **CLAIM**

The ornamental design for an apron combined with hooks, as shown and described.

DESCRIPTION

FIG. 1 is a front view of an apron combined with hooks, showing my new design, with parts of the straps shown broken away for convenience of illustration.

FIG. 2 is a left side view thereof; and,

FIG. 3 is a left perspective view illustrating the use of the present invention.

The broken line representation of a person sitting in a wheelchair is for illustrative purposes only and forms no part of the claimed design. Broken lines, other than the representation of a person sitting in a wheelchair, illustrate stitching.

The fragmentary cross-hatching shown in the drawing is understood to represent impermeable fabric and is repeated uniformly throughout all the areas shown.
